UNITED STATES PATENT OFFICE.

MARTIN A. BARBER, OF CLEVELAND, OHIO.

LOCK FOR AUTOMATIC CONNECTERS.

Application filed November 10, 1923. Serial No. 674,088.

This invention relates to automatic train pipe connecters and is particularly concerned with the provision of means for maintaining a close fitting engagement between connected heads when in coupled position.

A device for locking coupled connector heads heretofore used, embodies a spring pressed latch, which is carried by one head and is arranged to engage a shoulder in a coacting head. An objection frequently raised, however, to the spring pressed latch is the fact that the spring is apt to weaken or break whereupon the operativeness of the locking device is impaired.

One of the objects of my invention therefore, is the provision of a locking device which is positively actuated so as to effect a locking and an unlocking of coacting connector heads, without necessitating the use of yieldable means for actuating the locking device.

A further object of my invention is the attainment of a locking device which is quite simple in construction and which may be readily attached to existing automatic connecters.

The means for carrying out my invention will hereinafter be fully set forth in the following description which pertains to the accompanying drawings. The essential characteristics of my invention will be summarized in the claims.

In the drawings, Fig. 1 is a side elevation of a pair of coupled connector heads embodying my invention; Fig. 2 is a front view of an uncoupled head; Fig. 3 is a section taken on the line 3—3 in Fig. 2; Fig. 4 is a fragmentary section taken on an enlarged scale through a pair of connected heads; Fig. 5 is a vertical transverse section through the lock; Fig. 6 is a bottom plan view of an automatic connector having my invention applied thereto; and Fig. 7 is a detail view on an enlarged scale showing a bottom plan view of the connection between the ejector and the spring seat.

My invention is adapted for use with various forms of connecters but in the drawings I have illustrated it in connection with a form of automatic connector having a spring-pressed coupler head supported by the draw bar of a train coupler and provided on one side with a projection and on the other side with a recess. This construction is indicated in the various figures

wherein A indicates the draw bar of a railway car, B the coupler thereof, and C the bracket depending from the draw bar and carrying the automatic connecters to which the train pipes are adapted to be attached.

The automatic connector illustrated comprises a head 10 having orifices at 11, 12 and 13 for receiving the air signal pipe, the air brake pipe and the steam pipe respectively. These orifices, as shown, are arranged in a vertical line adjacent the center of the head and are positioned intermediate the projection 14 and recess 15. Each head is shown as having a shank 16 which has a sliding and universally movable connection with the bracket C and as having a strong compression spring 17 surrounding the shank which presses the head away from the bracket, so that in normally coupled position the springs are compressed.

My invention is concerned with the provision of a lock for retaining the connector heads in coupled position, and to this end I have illustrated my lock as comprising a plunger which is carried by one head so as to be movable relatively thereto, to effect a locking and unlocking action with a coacting connector head.

The locking mechanism shown in the present application embodies a casing 20 which has a hollow interior and which is arranged to be rigidly connected with the lower wall of the projection 14. The casing may have a pair of openings 21 and 22 which are arranged to align with an opening 23 in a plunger 25. An ejector 30 extends between the arms 26 formed by the opening 23 and also through the openings in the casing. A pin 27 may be carried by the plunger for operatively connecting it with the ejector. The plunger is adapted to be ejected from the casing for locking the coacting heads in coupled position and to be withdrawn into the casing to permit uncoupling of the heads.

The ejector comprises a relatively stationary member, one end 29 of which may be threaded to engage the spring seat 32 and the other end of which is provided with a slot through which the pin 27 extends. As shown in Figs. 6 and 7, the axis of the spring seat is in alignment with the axis of the threaded portion 29 of the ejector. An advantage of having the ejector carried by the seat is that neither vertical nor horizontal movement of the head with relation

to the bracket, causes movement of the ejector with relation to the plunger. Accordingly the coupled heads are maintained in locked position when the cars are rounding a 5 curve.

The walls of the slot provide a cam which moves the pin 27 so as to reciprocate the plunger whenever the head is moved with relation to the support therefor. The shape 10 of the cam slot is such that when the heads are in uncoupled position then the pin 27 occupies the upper reach 35 of the slot, in which position the plunger is withdrawn into the casing. When the heads are in cou- 15 pled position then the pin occupies the lower reach 36 of the slot which causes the plunger to be ejected from the casing. The downward movement of the pin 27 is caused by engagement with the inclined portion 38 20 which extends between the upper and lower reaches respectively. This inclined portion, moreover, is so arranged that the connector heads may be readily coupled and uncoupled without interference from the projecting 25 portion of the plunger.

To prevent damage to any of the operating parts of the locking device due to any cause which may prevent entrance of the plunger into the opening 39, I have provided 30 yieldable releasing means for permitting the ejector to move vertically with relation to the casing. In the preferred form, this means comprises an abutment, such as a washer 40 which is adapted to rest against 35 a shoulder 43 in the casing above the ejector. A spring 41 held in place by a cap 42 holds the washer in engagement with the shoulder. Under normal conditions, the plunger is moved vertically whenever the ejector is re- 40 ciprocated through the casing. In case an obstruction prevents the plunger from being ejected from the casing, then the force which tends to eject the plunger also tends to compress the spring 41, wherefore the ejector 45 may move upwardly with relation to the casing and thereby prevent shearing of the pin 27. The position of the ejector when raised with reference to the casing is illus- 50 trated in Fig. 5. The ejector is sufficiently long so that it may be sprung upwardly a sufficient amount to permit passage of the pin from the upper reach 35 to the lower reach 36.

Assuming that a pair of connector heads 55 are provided with a locking device made in accordance with my invention and assuming further that the cars to which the connectors are attached are uncoupled, then the pin 27 in each plunger will occupy the upper reach of the associated cam slot in the ejector 30, wherefore each plunger will be withdrawn into the associated casing. Assuming now that the cars are being coupled 60 then the initial coupling action causes the connector heads to be moved backwardly 65

with relation to the support, thereby compressing the springs 17 and causing the pins 27 to be moved backwardly and to approach the inclined portion 38 of each cam slot. As the head is being moved rearwardly the pins 70 27 are forced downwardly, thus causing the associated plungers to be ejected from the casing. When the plungers are ejected, then the heads are prevented from separating by reason of the fact that each plunger is 75 adapted to engage a shoulder 37 which comprises the wall of an opening 39 in the coacting recess. Upon the uncoupling of the cars the initial movement of the head relatively to the support causes the pins 27 to ascend 80 the inclined portions 38 of the associated cam slots, thus raising the plunger and withdrawing them into the casing, before the separating operation of the coacting head is accomplished. 85

In view of the foregoing description it will be understood that my invention provides means for insuring a positive actuation of the locking members consequent upon coupling and uncoupling of the cars. Moreover my invention embodies a simple device 90 which may be readily attached to existing connectors.

I claim:

1. In an automatic train pipe connector 95 the combination with a relatively stationary support, of a connector head, a plurality of members providing a universal connection between the head and support, a locking device carried by the head and an ejector extending forwardly of the support and co-operating with said device for coupling the head to be locked to a coacting connector head, said ejector being mounted on one of the first mentioned members whereby the 100 head may be either swung horizontally or moved vertically with reference to the support without causing relative motion of the ejector with reference to the head. 105

2. In an automatic train pipe connector 110 the combination with a connector head, of a support therefor, a universal joint between the head and the support, said joint including a spring seat movable upon a vertical axis, a latch carried by the head and movable with reference thereto for locking the head to a coacting connector head and a member mounted on the spring seat and co-operating with the latch to move the latch with reference to the head whenever the 115 head is moved in a longitudinal direction with reference to the support, the connection between the head and spring seat permitting the head to be swung horizontally with reference to the support without causing relative motion between the member and head. 120

3. In an automatic train pipe connector 125 the combination with a support, of a head having a shank thereon extending toward 130

the support, a spring surrounding the shank, a spring seat intermediate the spring and support, a plunger carried by the head and movable relatively thereto and means rigidly attached to the spring seat and operatively connected to the plunger for imparting motion to the plunger relatively to the head whenever the head is moved in a direction longitudinally of the shank and relatively to the spring seat, the connection between said means and spring seat permitting the head to be either swung horizontally or moved vertically with reference to the support without causing relative motion between said head and said means.

4. In an automatic train pipe connector, the combination with a connector head, of a support therefor, a rigid member associated with the support, said member having a cam slot therein adjacent the forward end thereof, a latch carried by the head, said latch having a portion thereof entering said cam slot whereby movement of the head in either a forward or backward direction with relation to the member effects a positive actuation of the latch.

5. In an automatic train pipe connector, the combination with a connector head, of a support therefor, a spring seat engaging the support, a relatively stationary member in threaded engagement with the seat, said member having a cam slot therein, said slot comprising an upper portion, a lower portion, and an inclined connecting portion, a latch carried by the head and operatively connected with the cam slot the latch being adapted to occupy the upper portion of the slot when the head is in uncoupled position and to occupy the lower portion of the slot when the head is in coupled position, and the walls of the inclined connecting portion functioning to move the latch positively in opposite directions during the coupling and uncoupling movement of the connector.

6. In an automatic train pipe connector, the combination with a head, of a supporting bracket therefor, a pivot block carried by the bracket, a spring seat bearing against said block, a shank carried by the head and projecting through the block and seat respectively, said head having a projection on one side and a recess on the other side, a

latch carried by the head within the projection, a rigid member for ejecting the latch upon movement of the head with relation to the bracket, said member being in threaded engagement with the spring seat, the axis of the threaded portion of said member extending parallel to the axis of the bearing between the spring seat and the pivot block.

7. In an automatic train pipe connector, the combination with a head, of a support therefor, a casing carried by the head, a plunger movable within the casing, an ejector member associated with the support and projecting through the casing and operatively connected with the plunger, whereby movement of the head towards the support is arranged to effect an ejection of the plunger from the casing, said casing having a shoulder above said member, a spring pressed abutment engaging the shoulder, said abutment being normally out of contact with the member, but adapted to be engaged thereby consequent upon failure of the plunger to be ejected from the casing when the head is moved with relation to the support.

8. In an automatic train pipe connector, the combination with a head, of a latch carried thereby, an ejector member operatively connected to the latch, yieldable means associated with the head and normally out of engagement with the ejector but adapted to yieldably resist movement thereof consequent upon failure of the latch to be actuated when the head is moved with relation to said member.

9. In an automatic train pipe connector, the combination with a head, of a casing carried thereby, a plunger movable within the casing, an ejector member operatively connected to the plunger, yieldable means carried by the casing and normally out of engagement with the ejector but adapted to yieldably resist movement of the ejector consequent upon failure of the plunger to be ejected from the casing when the head is moved with relation to said member.

In testimony whereof, I hereunto affix my signature.

MARTIN A. BARBER.
